UNITED STATES PATENT OFFICE.

GUSTAV A. OLSON, OF ALBERT LEA, MINNESOTA.

LITTER-CARRIER.

1,109,456.

Specification of Letters Patent. Patented Sept. 1, 1914.

Application filed December 7, 1912. Serial No. 735,463.

To all whom it may concern:

Be it known that I, GUSTAV A. OLSON, a citizen of the United States, residing at Albert Lea, in the county of Freeborn and State of Minnesota, have invented certain new and useful Improvements in Litter-Carriers; and I do hereby declare the following to be a full, clear, and exact description of the invention, such as will enable others skilled in the art to which it appertains to make and use the same.

My invention relates to litter carriers and is in the nature of an improvement on, or modification of that type of carrier which is disclosed and claimed in my prior Patent 978,332, of date, December 13th, 1910; but generally stated, the invention consists of the novel devices and combinations of devices hereinafter described and defined in the claim.

In the accompanying drawings which illustrate the invention, like characters indicate like parts throughout the several views.

Referring to the drawings, Figure 1 is a side elevation with some parts broken away, showing the improved carrier; Fig. 2 is a transverse vertical section taken on the line $x^2 x^2$ on Fig. 1; Fig. 3 is a horizontal section taken on the line $x^3 x^3$ on Fig. 1; Fig. 4 is a transverse section taken on the line $x^4 x^4$ on Fig. 3; Fig. 5 is a vertical section taken on the line $x^5 x^5$ on Fig. 4, some parts being shown in full; and Fig. 6 is a detail view in side elevation with some parts broken away illustrating the manner in which the cable guiding sheaves interlock with coöperating vertical channels, on the vertically movable bucket supporting bail.

The numeral 1 indicates a track rail shown as supported by hangers 2 from the suitable overlying supporting means 3. The track structure, however, may be of any suitable form and arrangement.

The bucket 4 is provided at its ends with trunnions 5 that are journaled in the depending ends of an inverted approximately U-shaped bucket supporting bail or frame 6.

Grooved truck wheels 7 run on the rails 1 and are journaled to small frames 8 to the intermediate portions of which the upper

ends of hanger brackets 9 are attached. The lower ends of the hanger brackets 9 are secured to a long horizontally extended truck frame 10. A long horizontal shaft 11 extended below the body of the truck frame 10 is journaled in suitable bearings thereon, and is provided with beveled pinions 12 that mesh with gears 13 secured on the ends of windlass drums 14 journaled in depending arms 15 of the said truck frame 10. These pinions 12 are reversely faced so that they will simultaneously rotate the two drums 14 in opposite directions at the same speed. A pair of bucket supporting cables 16 are wound upon and attached, one to each of the drums 14 and from the said drums the said cables are reversely extended, each past the drum upon which it is not wound, and over a guide sheave 17 journaled to bearing lugs on the said truck frame 10. The lower ends of the cables 16 are attached to the bucket supporting bail 6. Rigidly secured on the bail 6 adjacent to the points where the cables 16 are attached thereto are upwardly extended channel-shaped alining lugs 18, which, when the bail is raised, engage with the sheave 17 and hold the bail against endwise swinging movements.

Applied on a projecting end of the shaft 11 is a spring retracted driving wheel 19 provided with a depending operating cable 20. By drawing downward on said cable the shaft 11 will be positively rotated in a direction to cause the drums 14 and cables 16 to raise the bucket. Preferably, a pawl and ratchet device, such as disclosed in my prior Patent 978,332, of date December 13th, 1910, entitled "Litter carrier," is employed, as a connection between the wheel 19 and shaft 11, so as to permit the bucket to be raised by a succession of movements of the said wheel 19.

Secured on the shaft 11 is an externally toothed ratchet wheel 21 that is provided with a driving dog 22 that engages with internal teeth of a brake drum 23, which, as shown, is journaled on a hub 24, formed on one depending end of the truck frame 10 (see Figs. 4 and 5).

The numeral 25 indicates a lever-like re-

taining dog that is intermediately pivoted to a bearing 26 on the projecting end of the truck frame 10 and is engageable with the teeth of the ratchet wheel 21.

- 5 The numeral 27 indicates a tripping cable which is attached to and depends from the free end of the retaining dog 25. The numeral 28 indicates a divided arm, the ends of which are pronged and the sections of 10 which are yieldingly drawn together by a coöperating spring and bolt 29, which frictionally clamps the inner ends of the sections of said arm upon the shaft 11. The retaining dog 25 is provided with a depending 15 dog equipped with a tripping pin 30 that works between the prongs of the outer end of the arm 28. A stop pin 31 on the bearing 26 limits the movement of the said arm 28 in the direction of the arrow marked 20 on the ratchet wheel 21, on Fig. 4. Also the said stop 31 limits the movements of the said arm 28 in the opposite direction.
- 25 The numeral 32 indicates a flexible brake band that engages the brake drum 23 and has its ends attached to a brake lever 33, pivotally connected to a projecting arm 34 of the truck frame 10 (see Fig. 4). Attached to the free end of the arm 33 is an operating cable 35 which is passed over a 30 guide sheave 36 journaled on a bracket 37 on the truck frame 10. The brake lever 33 is provided with an upwardly extended arm 33^a that is connected by a spring 38 to the bearing 26, or other part on the truck 35 frame 10.

The operation summarized is substantially as follows: The shaft 11 may be rotated in the direction of the arrow marked on Fig. 4 with a step by step movement, by 40 successively pulling on and releasing the cable 20, as already indicated, and the retaining dog 25 operating on the ratchet wheel 21 will hold the said shaft, and hence the windlass drum 14 where set, and this 45 will hold the bucket 4 at any desired elevation. When the carrier is to be moved with the load, the bucket supporting bail 6 will be elevated so that the alining channels 18 engage with the wheels 17. The two drums 50 14 being simultaneously rotated in reverse directions, will simultaneously wind up the cables 16 and thereby evenly lift the bucket supporting bail 6 at both ends.

In my prior patent, above identified, two 55 cables were employed, but both were wound on the same drum. I have found that a better action may be produced by the two simultaneously operating drums and that better cable movement can be had by two 60 drums than by a single drum, for the obvious reason that two drums have a greater cable holding capacity than a single drum. The cables should be attached to the respective drums on the same side of the carrier, 65 (see Fig. 3), so that they accumulate or

wind up on the drums by lateral movement in the same direction which permits the cables to be closely brought together without producing a conflict between the movements of the two cables.

When it is desired to lower the bucket, it is only necessary to draw down on the cable 27 so as to thereby release the retaining dog 25 from the ratchet wheel 21. When this has been done, the bucket will 70 not immediately lower because the brake band 32 under the tension of the spring 38 is tightly set upon the brake drum 23, and at such time, rotation of the shaft 11 and drums 14 is prevented by engagement of the dog 22 with the internal ratchet teeth of the said brake drum 23. By then drawing downward on the cable 35, however, the brake band 32 may be released from the drum 23 just to the desired extent to 75 permit the loaded bucket to lower under the action of gravity. The initial movement of the shaft 11 in the direction just stated, to wit, in the direction reverse from that indicated by the arrow on Fig. 4, carries the frictional arm 28 in the same direction, and the latter acting on the stud 30 of the retaining dog 25 holds the latter in an inoperative position, while the bucket is being lowered. When the bucket is being 80 raised by manipulation of the cable 20, as already described, it is not necessary that the brake drum 23 move, inasmuch as the dog 22 will slip over the internal ratchet teeth thereof. When the bucket is being 85 raised by movement of the shaft 11 in the direction of the arrow shown on Fig. 4, the frictional arm 28 moves with said shaft in the same direction, and acting on the stud 30, automatically carries the retaining 90 dog 25 back to its operative position. It will thus be seen that the shaft 11 must move with the drum 23 when the bucket is being lowered, but that the said shaft and the windlass drums 14, may move independently of the said brake drum 23 when the bucket is being raised. Also, it has been noted that the retaining dog 25 and the 95 brake band 32 are operated by manipulation of two independent cables or operating 100 connections. The mechanism described has, in actual practice, been found highly efficient for the purposes had in view.

What I claim is:

The combination with a truck arranged to 105 travel on an elevated track, of a bucket supporting frame, a bucket pivotally connected to said frame, a pair of windlasses and a pair of cable guiding wheels carried by and spaced in reverse arrangement longitudinally of said truck, cables independently attached one to each of said windlass drums and extended in reverse directions over said cable guiding wheels and thence downward and attached to said bucket supporting 110

frame, said cables being attached to said windlass drums on the same side of said truck, a shaft carried by and extended longitudinally of said truck, and gears connecting said shaft to said windlass drums and arranged to simultaneously rotate the same in reverse directions.

In testimony whereof I affix my signature in presence of two witnesses.

GUSTAV A. OLSON.
